[57] CLAIM

The design for a code scanner for automotive diagnostic testing, as shown and described.

DESCRIPTION

FIG. 1 is a top, front and right side perspective view of a code scanner for automotive diagnostic testing showing my new design;

FIG. 2 is a top plan view, the bottom plan view being a mirror image;

FIG. 3 is a rear elevational view;

FIG. 4 is a front elevational view; and,

FIG. 5 is a right side elevational view thereof, the left side elevational view being a mirror image.

FIG1

FIG.5

FIG.2
